United States Patent Office

Des. 218,511

Patented Aug. 18, 1970

218,511

BOOKMARK OR THE LIKE

Robert B. Sarro, 416 Burkhard St.,
Mineola, N.Y. 11501

Filed Mar. 12, 1969, Ser. No. 16,201

Term of patent 7 years

Int. Cl. D19—99

U.S. Cl. D97—2

Fig. 1.   Fig. 2.   Fig. 3.

FIG. 1 is a front perspective view of a bookmark or the like showing my new design;

FIG. 2 is a side elevational view; and

FIG. 3 is a rear elevational view thereof.

I claim:

The ornamental design for a bookmark or the like, substantially as shown.
